UNITED STATES PATENT OFFICE.

JESSE C. OWENS, OF LOS ANGELES, CALIFORNIA.

MUFFLER TOILET TANK.

1,426,094.

Specification of Letters Patent. Patented Aug. 15, 1922.

Application filed May 16, 1921. Serial No. 469,756.

To all whom it may concern:

Be it known that I, JESSE C. OWENS, a citizen of the United States, and resident of Los Angeles, county of Los Angeles, State 5 of California, have invented new and useful Improvements in a Muffler Toilet Tank, of which the following is a specification.

This invention relates to improvements in closet tanks and pertains especially to the 10 construction for delivery of water thereto.

The objects of this invention are first, to provide a tank structure whereby the delivery of water thereto for filling the same is noiseless; second, to provide a structure 15 of the character described which is self contained and has a minimum of independent fittings; and third, to provide a structure with a novel refill and overflow conduit.

These objects together with other objects 20 and corresponding accomplishments are obtained by means of the embodiment of my invention illustrated in the accompanying drawing, in which:

Fig. 1 is a plan view of the tank; and Fig. 25 2 is a vertical section with parts shown in elevation.

Referring more particularly to the drawing, A indicates the tank. B indicates the flush valve controlling the discharge to the 30 bowl. The supply cock is indicated generally by C and controls the flow of water to the tank. My novel filling basin which may be formed integral with the tank is indicated by D.

35 Referring more in detail to the tank A, it is preferably formed integral with a supply passage 3 extending vertically through one of the side walls. A nipple 4 is mounted in the tank and in communication with conduit 3, thereby providing for connection to the house service pipe. The upper end of the passage 3 opens through the wall communicating with a valve chamber formed in a block 5. This block is fastened to the 45 wall by any convenient means and has formed therein a valve seat for a valve disk 6. The valve disk is provided with a stem 7 slidably extending through an opening in the block. Chamber 8 is formed in the block 50 and communicating therewith is a passage 9. The passage 9 connects with a passage 10 extending along the side wall and along the rear wall. Joining the passage 10 and leading downwardly are passages 11 and 55 12 communicating with the filling basin D.

The basin D is circular in horizontal sec-

tion and slightly undercut. At the center thereof is a threaded opening to receive a nipple 13 for connection to the pipe leading to the bowl and forming a valve seat. The 60 passages 11 and 12 are connected to the basin by ducts 14 and 15, which direct the water into the basin tangentially so that it will have a whirling motion.

Seated over the discharge opening in the 65 basin is a float valve 16 having a stem 17 guided in a bracket 18. The opening in the bracket 18 through which the stem extends flares outwardly toward the top to provide for the float valve properly aligning itself 70 in seating. The top of the stem is provided with a button, and a link 19 engages the button. The link 19 is connected to a handle tank lever 20, whereby rocking of the same will lift the float valve 16.

The stem 7 is connected by a sliding joint 21 to a float valve lever 22 pivotally mounted upon a bracket 23.

Assume that the tank is full of water, 80 float valve 16 being upon its seat and closing the discharge port. The ball float 23 will be in its upper position, thereby holding valve 6 upon its seat and closing off the flow of supply water. Handle 20 may then be rocked to the right, thereby lifting the 85 valve 16 from its seat. Water will then flow through the discharge nipple to the bowl. As the water level drops, float 23 drops and thereby opens the valve 6 permitting water to flow through passage 3, chamber 8, passage 9, passage 10, passages 11 and 12 to ducts 14 and 15 and into the filling basin. The water enters the filling basin in a tangential direction and without noise. Float 90 valve 16 seats upon the nipple, as soon as 95 the tank has been drained, and the tank is filled. As the upper level of the water is reached, ball float 23 is raised, closing the valve 6 and cutting off the flow of supply water.

Extending parallel to the passage 12 is a 100 refill and overflow passage 24. The upper end of the refill and overflow passage is connected by a port 25 to passage 12, this port constituting a refill port. At the upper 105 water level a port 26 connects the passage 24 with passage 12. The lower end of passage 24 is connected by a passage 27 to a point below the float valve 16. Thus, after the valve 16 has seated, water may flow through port 25, passages 24 and 27 and into nipple 13 so as to refill the bowl. If valve 6 does 110

not seat tightly or water flows through the valve for any reason after the tank has been filled, it will escape through port 26, passages 24 and 27 to the bowl, thereby preventing overflowing of the tank.

The novelties in my invention reside in the disposal of the passages in the wall of the tank, and the filling basin, which results in the tank being filled noiselessly.

10 What I claim is:

1. A flush tank for toilets comprising a reservoir having formed in the wall thereof a supply water passage, a valve chamber communicating with said supply water passage, a water distributing passage formed in the wall of said reservoir and leading from said chamber, a circular filling basin formed in the bottom of said reservoir, said distributing passage communicating with said 15 basin and directing water thereinto in a tangential direction, a discharge port at the center of said basin, a float flush valve for said discharge port, linkage to lift said flush valve, an intake valve for said valve chamber, and float actuated means for operating said intake valve, said reservoir having an 20 overflow and refill passage formed therein and opening below said flush valve with a port connected to said distributing passage 25 and said overflow and refill passage at the high water level.

2. A flush tank for toilets comprising a reservoir having formed in the walls thereof a supply water passage, a valve chamber 30 communicating with said passage, a distributing water passage formed in the wall of 35

said reservoir and leading from said chamber so as to discharge water into said reservoir, a discharge port at the bottom of said reservoir, a flush valve for said discharge port, means to lift said flush valve, an intake valve for said valve chamber, and float actuated means for operating said intake valve, said reservoir having an overflow and refill passage formed therein, an opening below said 40 flush valve, a port connected to the distributing passage and to said overflow and refill passage at the high water level.

3. A flush tank for toilets comprising a reservoir having a circular filling basin formed in the bottom thereof, a conduit for supply water leading to said basin and directing water thereinto in a tangential direction, a float actuated valve controlling the flow of water to said basin, a discharge port 50 at the center of said basin, a float flush valve for said discharge port, and means to lift said flush valve.

4. A flush tank for toilets comprising a reservoir having formed in the bottom thereof a circular filling basin, a conduit leading to said basin for directing supply water thereinto in a tangential direction, an intake valve actuated by a float controlling the flow of water through said conduit, a discharge 55 port for said tank, and a flush valve for said discharge port.

In witness that I claim the foregoing I have hereunto subscribed my name this 6th day of May, 1921.

JESSE C. OWENS.
